TELEVISION PROGRAM REMINDER SYSTEM BOARD

Joseph Robert Bren, 1133 N. Hacienda Place,
Los Angeles, Calif.

Filed Feb. 19, 1962, Ser. No. 68,871

Term of patent 14 years

(Cl. D25—1)

FIG. 3.

FIG. 4.

FIG. 5.

FIG. 1 is a front elevational view of a television program reminder system board showing my new design;

FIG. 2 is a top plan view thereof;

FIG. 3 is an end elevational view thereof;

FIG. 4 is a sectional view taken on line 4—4 of FIG. 1; and

FIG. 5 is a fragmentary sectional view taken on line 5—5 of FIG. 1.

The essential features of my design reside in the full line showings on the drawings. The rear of the board is substantially similar to the front. The broken line showing of the peg in FIGS. 1 and 2 is for illustrative purposes only.

I claim:

The ornamental design for a television program reminder system board, substantially as shown and described.
